UNITED STATES PATENT OFFICE.

ARNOLD STUCKI, OF ALLEGHENY, PENNSYLVANIA, ASSIGNOR TO STANDARD STEEL CAR COMPANY, OF PITTSBURG, PENNSYLVANIA, A CORPORATION OF PENNSYLVANIA.

METALLIC RAILWAY-CAR.

SPECIFICATION forming part of Letters Patent No. 752,309, dated February 16, 1904.

Application filed August 13, 1903. Serial No. 169,358. (No model.)

To all whom it may concern:

Be it known that I, ARNOLD STUCKI, a resident of Allegheny, in the county of Allegheny and State of Pennsylvania, have invented a new and useful Improvement in Metallic Railway-Cars; and I do hereby declare the following to be a full, clear, and exact description thereof.

My invention relates to railway-car underframes; and its object is to provide an underframe having a very high carrying capacity and which supports the floor as low as possible.

In many relations it is desirable to have a car having a very high carrying capacity, and in order to facilitate the loading of heavy machinery, castings, &c., thereon it is desirable to have the floor supported as short a distance above the rails as possible. With cars of very high carrying capacity it is necessary to use six-wheeled trucks in order to distribute the load over a sufficient rail-length. With such trucks there is not room enough to use a fish-belly center sill, and consequently but little of the load can be carried at the center of the car, but must be carried mostly by the side sills. As a consequence the latter must be made very deep in order to get the necessary strength. Inasmuch as the width of the car is limited by the clearance-lines of bridges and tunnels and as the six-wheeled trucks by reason of their length require considerable lateral space in passing around curves, some special construction of side sills must be provided to permit the trucks to pass properly around curves.

The object of my invention is to provide a car - underframe adapted for the purposes above specified and wherein the proper clearance for the trucks and also the necessary strength is secured.

To this end it consists in a car-underframe having peculiar and especially - constructed side sills of very great depth, so as to get the necessary carrying capacity, said sills being cut away opposite the journal-boxes of the truck, so as to permit lateral movement of said journal-boxes when the truck swings around curves.

The invention also comprises other details of construction hereinafter specified and 50 claimed.

In the accompanying drawings, Figure 1 is a plan view of one-half of my improved underframe. Fig. 2 is a side view of the same. Fig. 3 is a central longitudinal section through 55 the same. Fig. 4 is an end view thereof. Fig. 5 is a cross-section on the line 5 5, Fig. 1. Fig. 6 on its right-hand portion is a cross-section on the line 6 6, Fig. 1, and on its left-hand portion on the line 6^a 6^a, Fig. 1; and Fig. 7 is a side view of a modification.

In order to better illustrate the principle of my invention, I have shown in several of the views the outline of a truck for supporting the underframe. This truck comprises 65 the wheels 1, axles 2, journal-boxes 3, side frames 4, bolsters 5, bridge 6, cross-bearer 7, and center bearing-plate 8. The constructions of these several parts of the truck are fully illustrated, described, and claimed in an 70 application of even date herewith, Serial No. 169,357, and specific description thereof will not be made in the present case. Any form of six-wheeled truck of sufficient strength to 75 carry the necessary load may be used in connection with my underframe, although the truck shown is peculiarly adapted for carrying the underframe very close to the rails.

On account of the great length of six-wheeled trucks and the construction thereof 80 there is not room enough to use fish-belly center sills. Consequently straight center sills 10, preferably rolled channel-beams of moderate depth, are employed. These sills will take care of all of the end shocks, but will carry 85 only a small portion of the load. The latter is carried almost exclusively by the side sills 11, which are made very strong and which project down considerably below the journal-boxes 3. The clearance in tunnels and bridges 90 limits the width of the cars, and consequently these side sills cannot be placed too far apart, and inasmuch as the six-wheeled trucks in passing around curves swing laterally to a considerable extent there is danger of the journal-boxes coming in contact with these low-hang- 95

ing side sills. As a consequence the side sills are so constructed that they are open opposite the journal-boxes. In Fig. 7 this principal is clearly shown, wherein the side sills are of plate-girder construction and provided with holes 12 opposite the journal-boxes. Preferably, however, the side sills are of an open-trussed or lattice girder construction, having the lattice-work so arranged that open spaces 10 will be left opposite the journal-boxes. This latter form of side sills is shown in other figures of the drawings. These side sills each comprise a plate 13, having its upper edge substantially at the floor-level and projecting 15 downwardly approximately one-third of the depth of the sill. Riveted to this plate is an angle-bar 14, which, together with the plate, forms the upper or compression member of the girder. The lower or tension member of 20 the girder is formed by a flanged member, such as the angle bar 15, and this may be further strengthened by a section of plate 16, if desired. The top and bottom members of the sill are connected by suitable vertical members 17 and diagonal members 18, which are riveted either directly to said members or connected thereto by means of connecting-plates 19. These vertical and diagonal members are 25 arranged, as shown in Fig. 2, to leave open spaces or openings opposite the journal-boxes 3, so as to permit the free lateral movement of the trucks in passing around curves and also to facilitate inspection of the journal boxes and 30 bearings.

35 The longitudinal members of the underframe are connected at intervals by means of the shallow cross-ties 20, which may be of any preferred form and are shown as pressed pan-shaped plates placed between the side and center sills and also between the center sills. At 40 two points near the middle of the underframe are deeper cross-ties or diaphragms composed of filling-pieces 22, placed between the side and center sills and also between the center 45 sills, said filling-pieces being substantially the same depth as the center sills, and a cross-connecting member 23, placed underneath these filling-pieces and preferably secured thereto, as shown in Fig. 5, and extending from side 50 sill to side sill and secured thereto. All of the members of these cross-ties—that is, the filling-pieces 22 and the cross-pieces 23—are formed of pressed pan-shaped members, thus providing flanges for securing the same to the 55 car-sills and to each other. These cross-connecting members, however, may be other than pan-shaped members, if desired.

At the ends of the underframe the downwardly-projecting portions of the side sills 60 are connected and held in place by means of diagonal rods 25, having one end secured to the lower chords of the side sills and the opposite ends secured to the lower edge of the end sill. The end sill may be of any preferred 65 construction, but preferably is a pressed chan-

nel-shaped member of the cross-section shown in Fig. 3, having an opening 27 therethrough for the passage of the shank of the draw-bar and preferably having a bulged-up portion 28 at its middle to give it sufficient strength above 70 the draw-bar opening, this being necessary because said opening must be placed relatively high by reason of the low position of the underframe. The draft-lugs 30 are riveted directly to the center sills, and to give sufficient 75 space for the draft-rigging the floor-plates are bulged upwardly near the end at the center of the car, as shown at 31.

The body-bolster 32 is placed above the sills, this being necessary because of the low position of the underframe, which leaves insufficient space between the truck-bolster and the center and side sills. The body-bolster may be of any suitable beam construction, that shown being an inverted trough member having outwardly-turned flanges 33 at its lower edge for riveting to the longitudinal sills. This trough is strengthened at the ends by braces 34 and at the middle by braces 35. Filling pieces or brackets 37 of the form shown in 90 Fig. 6 and preferably formed of pressed metal are placed in the angle between said bolster and the outer faces of the center sills and riveted to both. Brace-pieces 39 are riveted to the center and side sills and lower edges of 95 the cross-tie pieces 20. The floor-plates 39 are riveted directly to the upper flanges of the longitudinal sills and also to the cross-tie members and to the outwardly-projecting flanges of the body-bolsters. Although this arrangement of floor-plates is shown in this case, it 100 will be understood that a wooden floor may be used.

The underframe described is very strong and carried very low, thus facilitating the loading 105 and unloading of heavy objects. Furthermore, it is as narrow as is possible with such deep side sills and affords ample clearance for bridges and tunnels.

What I claim as my invention, and desire to 110 secure by Letters Patent, is—

1. In a railway-car, the combination with bogie-trucks having journal-boxes outside the wheels, of an underframe comprising suitable cross members and deep side sills connected thereto and projecting downwardly below the 115 level of the truck journal-boxes and having openings therethrough opposite said boxes of larger size than said boxes.

2. In railway-cars, the combination with bogie-trucks having journal-boxes outside the wheels, of an underframe comprising cross members and trussed-girder side sills secured thereto and projecting downwardly below the level of the truck journal-boxes and having 125 vertical and diagonal members so arranged as to leave open spaces opposite the journal-boxes of larger size than said boxes.

3. In railway-cars, the combination of bogie-trucks having journal-boxes outside the 130

- wheels, of an underframe comprising center sills of moderate depth, side sills of greater depth and having their upper edges substantially level with the upper edges of the center sills and provided with openings opposite the truck journal-boxes of larger size than said boxes, and cross members connecting said center and side sills.
4. A car-underframe comprising suitable cross members and trussed side sills connected thereto, said side sills comprising top and bottom members, the top member being formed of a plate and a flanged bar arranged substantially at the level of the floor, a flanged bar forming the bottom member, and vertical and diagonal bars connecting said top and bottom members.
5. A car-underframe comprising center sills of moderate depth, side sills of greater depth, filling-pieces between the center and side sills of substantially the depth of the center sills, and a cross connecting member secured to the downwardly-projecting parts of the side sills and to the filling-pieces.
6. In a car-underframe, the combination of body-bolsters, center sills of moderate depth extending from body-bolster to body-bolster, side sills of greater depth than the center sills and placed with their upper edges on substantially the same level as the upper edges of the center sills, and cross tie members con-

necting the downwardly-projecting portions of the side sills.

7. A car-underframe comprising center sills of moderate depth, side sills of much greater depth, said side and center sills being placed with their upper edges in substantially the same plane, suitable cross connecting members between said sills, and diagonally-arranged rods secured to the downwardly-projecting portions of the side sills and to the underframe at substantially the level of the lower edges of the center sills.

8. In a car-underframe, the combination with the center sills of moderate depth, side sills of greater depth and projecting below the former, bolsters located above said sills and secured thereto, and brace-pieces secured to the center sills and to the bolsters.

9. An end sill for railway-cars comprising a flanged beam provided with an opening for the passage of the draw-bar shank and having an embossment integral therewith and lying above the draw-bar opening and projecting above the body of the sill.

In testimony whereof I, the said ARNOLD STUCKI, have hereunto set my hand.

ARNOLD STUCKI.
